Patented Dec. 18, 1923.

1,477,691

UNITED STATES PATENT OFFICE.

JÜRGEN CALLSEN, OF ELBERFELD, GERMANY, ASSIGNOR TO FARBENFABRIKEN VORM. FRIEDR. BAYER AND CO., OF LEVERKUSEN, NEAR COLOGNE-ON-THE-RHINE, GERMANY.

PHARMACEUTICAL PRODUCT.

No Drawing.

Application filed January 2, 1923. Serial No. 610,364.

To all whom it may concern:

Be it known that I, JÜRGEN CALLSEN, a citizen of Germany, residing at Elberfeld, Marienstrasse 106, in the State of Prussia,

5 Germany, have invented new and useful Improvements in Pharmaceutical Products, of which the following is a specification.

It has been found that saturated or unsaturated hydroaromatic ketones which 10 contain an isopropyl side chain in meta position to the keto group (see Crossley and Pratt, Journal of Chem. Soc., London 107 page 171; Annalen der Chemie 277, page 133 and 288, page 328) furnish pharmaceutically valuable solutions by treating these 15 products with solutions of salts of organic acids. As these ketones show a valuable analeptic action like that of camphor my new solutions represent valuable pharmaceutical preparations, an average dose for 20 subcutaneous use being about 0.02 grams of the ketone for an intravenous and 0.2 grams for an intra-muscular injection.

In order to illustrate my new invention 25 more fully the following example is given:—

500 grams of 3-methyl-5-isopropyl- Δ -2-cyclo-hexanon (Annalen der Chemie 288, page 328) are mixed together with 500 cubic 30 centimeters of a 50 per cent aqueous solu-

tion of sodium salicylate (1 cubic centimeter=0.5 gram sodium salicylate). A limpid solution results which can be further diluted with water without a precipitate being obtained.

Other of the above mentioned ketones may be used, e. g. 3-methyl-5-isopropylcyclohexanon, 1-isopropylcyclohexan-3-on (Journ. of Chem. Soc., London 107, page 171), etc. Instead of sodium salicylate other salts of 40 organic acids may be used, e. g. sodium benzoate, the sodium salt of meta-oxybenzoic acid, the potassium salt of isovaleric acid etc.

I claim:—

1. The hereinbefore described new solutions of hydroaromatic ketones containing an isopropyl side chain in meta-position to the keto group in solutions of salts of organic acids, being valuable pharmaceutical 50 products as analeptics, substantially as described.

2. The herein described new solution of 3-methyl-5-isopropyl- Δ -2-cyclohexanon in an aqueous solution of sodium salicylate, 55 being a valuable pharmaceutical product as an analeptic, substantially as described.

In testimony whereof I have hereunto set my hand.

JÜRGEN CALLSEN.
